CLAIM

The ornamental design for a storage box, as shown and described.

DESCRIPTION

FIG. 1 is a left side view of the first embodiment of a storage box, showing our new design;

FIG. 2 is a front view thereof;

FIG. 3 is a rear view thereof;

FIG. 4 is an exploded perspective view thereof;

FIG. 5 is a top view thereof;

FIG. 6 is a bottom view thereof;

FIG. 7 is a right side view thereof;

FIG. 8 is a front view of the second embodiment of the storage box, showing our design;

FIG. 9 is a left side view of thereof;

FIG. 10 is an exploded perspective view thereof;

FIG. 11 is a top thereof; and,

FIG. 12 is a bottom view thereof.

The portions of the storage box shown in dashed lines form no part of the claimed design.
